AUXILIARY DEVICE FOR FABRIC HOLDING-DOWN ATTACHMENTS

Woldemar Heinitz, Chemnitz, Germany, assignor
to Schubert & Salzer Maschinenfabrik Aktien-
gesellschaft, Chemnitz, Germany

Application June 3, 1936, Serial No. 83,363
In Germany December 6, 1935

4 Claims. (Cl. 66—82)

The present invention relates to auxiliary devices for holding down the fabric on straight knitting machines.

As is well known, such auxiliary devices for holding down the heel portions of a stocking are, during the manufacture of the leg portion, swung backwardly into an inoperative position or a position of rest, whereas after finishing the leg portion they are swung into the operative position at which time the instep needles are placed in suspense. Moreover, in each division the distance between the associated holding down devices, occupying the operative position, must be smaller than the width of the leg portion.

Therefore, during swinging the holding down devices into the operative position as well as into the inoperative position, the danger exists, that the holding down devices come into contact with the fabric and easily cause damages of the leg portion of the stocking.

The object of the present invention is to obviate the above mentioned drawbacks and to obtain this end, means are provided for preventing contact between the leg portion and the holding down devices during swinging of the latter into and out of the operative position.

In the accompanying drawings some embodiments of devices according to the present invention are shown by way of example.

In these drawings:

Fig. 1 is a side elevation of one embodiment of the invention,

Fig. 2 illustrates a plan view of the device shown in Fig. 1,

Figs. 3 and 4 show a part sectional side elevation and a plan view respectively of a modification of the device according to the invention,

Fig. 5 is a detail view,

Figs. 6 and 7 show a plan view and a side elevation partly in section respectively of a further modification of the device according to the invention, and

Fig. 8 is a perspective view of the device shown in Figs. 6 and 7.

The same reference characters are used to designate corresponding parts of the different figures.

According to the construction shown in Figs. 1 and 2, two bearings 2 are fixed to the frame 1 of the knitting machine. Rotatably mounted in the bearings 2 are sleeves 3 which carry two rods 4 and 5 having a non-circular cross section and adapted to be shifted in the longitudinal direction with regard to each other. In each division

a holding down finger 6 is mounted upon the rod 4 and a holding down finger 7 upon the rod 5.

During the manufacture of the leg portion, the holding down fingers 6 and 7 are, as shown in dash-and-dotted lines in Figs. 1 and 2, swung 5 backwardly and may occupy any position in the division.

If the manufacture of the heel portions is started and the holding down fingers 6 and 7 do not occupy already the position shown in 10 dash-and-dotted lines in Fig. 2, they must be brought out of the range of the leg portion by shifting the rods 4 and 5 with respect to each other. Without the danger of coming into contact with the leg portion, the holding down fingers 6 and 7 may then be brought into the position shown in dotted lines in Fig. 2, whereupon the rods 4 and 5 can be shifted with respect to each other until the holding down fingers 6 and 7 occupy the operative position, shown in full 20 lines in Fig. 2, in which they may bear against the loops of the heel portions to hold them off the sinkers 8.

After finishing the manufacture of the heel portions, the rods 4 and 5 are shifted in opposite 25 direction to separate the holding down fingers 6 and 7 from each other so far, that they may be swung into the position of rest without danger of coming into contact with the fabric and 30 damaging the latter.

In the modified construction of the device shown in Figs. 3-5, holding down arms 9 and 10 are rotatably mounted upon a shaft 11 journaled in the bearings 2. Adjustable rings 12, 13 and 14, 15 respectively serve to prevent shifting of 35 the arms 9 and 10 in axial direction of the shaft and to hold them separated from each other in a distance suitable for holding down the heel portions.

Near the frame 1 of the knitting machine, 40 wires or rods 16 and 17 extending all over the length of the machine are provided upon which slides 18 and 19 are adjustably arranged.

The holding down arms 9 and 10 occupy, during the manufacture of the leg portion, the position shown in dash-and-dotted lines in Fig. 3. At the beginning of the manufacture of the heel portions, the shaft 11 is turned by means of the handle 20, so that the holding down arms 9 and 10 are brought into the position shown in 45 full lines in Figs. 3 and 4. The distance between the arms 9 and 10 is always suitable for holding down the heel portions of a stocking. To prevent the leg portion coming into contact with the holding down arms, the wires or 50 55

- rods 16 and 17 respectively are shifted with respect to each other so far, that the distance between the slides 18 and 19 is smaller than the smallest distance between the holding down arms 9 and 10, so that, as shown in dash-and-dotted lines in Fig. 4, the edges of the fabric are shifted against each other and a contact between the latter and the holding down arms is prevented, whereby damaging of the fabric is impossible.
- 10 According to the modification of the new device shown in Figs. 6-8, the holding down arms 9 and 10, rotatably mounted upon the shaft 22, also permanently have a distance from each other suitable for holding down the heel portions.

15 In bearings 23 of the frame 1 of the machine, a shaft 24 is rotatably arranged. In each division, a plate 25 is fixed to the shaft 22. The middle portion of the plate 25 is cut away and 20 the connecting edges 26, 27 between the small middle portion 30 and the large side portions 28 and 29 respectively are formed as inclined curves as may best be seen from Fig. 6. The plate 25 simultaneously serves to cover the holding down 25 devices in the position of rest.

If the holding down arms 9 and 10 are not used, the plate 25 is brought into the position shown in full lines in Figs. 6 and 7, to prevent hurting of the operator by the draw off hooks 30 31 and 32 provided at the arms 9 and 10 respectively.

As soon as the manufacture of the heel portions is started, the plate 25 is swung into a vertical position, indicated in dash-and-dotted lines 35 Fig. 7, so that, as clearly shown in the perspective view (Fig. 8), the longitudinal edges of the fabric 21 are shifted against each other in such a manner, that the width of the fabric is smaller than the distance between the holding down 40 arms 9 and 10. The holding down devices may now be swung into the operative position without coming into contact with the fabric. After the completion of the heel portions, the plate 25 is again swung in the position shown in Fig. 8, 45 so that, during movement of the arms 9 and 10 into the position of rest, there is no danger of damaging the fabric 21.

What I claim is:

1. An auxiliary device for holding down attachments, acting upon the fabric during the manufacture of the heel portions upon straight knitting machines adapted to produce stockings

5 in a single operation and to knit the heel portions while the needles, producing the instep portion of the stocking, are placed in suspense, comprising means for preventing contact between the holding down devices and the leg portion of the stocking during swinging the holding down devices into and out of the operative position.

2. An auxiliary device for holding down attachments, acting upon the fabric during the manufacture of the heel portions upon straight knitting machines adapted to produce stockings in a single operation and to knit the heel portions while the needles, producing the instep portion of the stocking, are placed in suspense, 10 comprising bearings, a sleeve rotatably mounted in each of said bearings, and two rods of a non-circular cross section arranged in contact with each other and adapted to be shifted with respect to each other in the longitudinal direction, 15 one of said rods carrying the parts of the holding down devices provided at the right hand side of the middle of each division of the machine, while the other of said rods carries the parts of the holding down devices arranged at 20 the left hand side of the middle of each division of the machine.

3. An auxiliary device for holding down attachments, acting upon the fabric during the manufacture of the heel portions upon straight knitting machines adapted to produce stockings in a single operation and to knit the heel portions while the needles, producing the instep portion of the stocking, are placed in suspense, 30 comprising two draw elements, extending all over 35 the length of the machine, and a slide for each division adjustably mounted upon each of the draw elements.

4. An auxiliary device for holding down attachments, acting upon the fabric during the manufacture of the heel portions upon straight knitting machines adapted to produce stockings in a single operation and to knit the heel portions while the needles, producing the instep portion of the stocking, are placed in suspense, 40 comprising a swingably arranged plate for each division, the ends of said plate being larger than the middle portion, and the connecting edges between the large ends and the small middle portion being formed as inclined curves extending inwardly.

WOLDEMAR HEINTZ.
